DESIGN FOR AN INVERTED GAS-BURNER.

No. 38,348.

Specification for Design.

Patented Dec. 11, 1906.

Application filed October 27, 1906. Serial No. 340,926. Term of patent 14 years.

To all whom it may concern:

Be it known that I, THOMAS J. LITTLE, Jr., of Gloucester City, Camden county, New Jersey, have invented a new, original, and ornamental Design for an Inverted Gas-Burner, reference being had to the accompanying drawing, forming part of this specification, which is a perspective view of a gas-burner embodying my design.

I claim—

The ornamental design for an inverted gas-burner, as shown.

In testimony whereof I have hereunto set my hand.

THOMAS J. LITTLE, JR.
